UNITED STATES PATENT OFFICE.

JOHN ROYDEN PEIRCE, OF NEW YORK, N. Y., ASSIGNOR TO COMPUTING-TABULATING-RECORDING CO., OF NEW YORK, N. Y., A CORPORATION OF NEW YORK.

RECORD SHEET AND APPARATUS CONTROLLED THEREBY.

Application filed June 7, 1922. Serial No. 566,448.

To all whom it may concern:

Be it known that I, JOHN ROYDEN PEIRCE, a citizen of the United States of America, residing at New York, county and State of 5 New York, have invented certain new and useful Improvements in Record Sheets and Apparatus Controlled Thereby, of which the following is a full, clear, and exact description.

10 The present invention is directed to improvements in card controlled machines.

Perforated record cards have come to be generally used for the keeping of records of various sorts. These cards after being 15 properly perforated may be passed through machines of various types which read the perforated data upon the cards and combine the same in various ways. Certain types of machines generally known as tabulating 20 machines are adapted to accumulate data from successive cards. Others not only accumulate but record individual records and totals.

The present invention has for one of its 25 objects the provision of an improved system of perforations for the record cards which system greatly extends the class and character of records which may be kept on the cards and also keeps the dimensions of 30 the cards within practicable limits.

A further object of the present invention resides in the provision of an improved machine for handling perforated record cards, taking off readings therefrom and 35 transferring these readings to other record sheets or cards which are passed through the machine.

A further object of the present invention resides in the provision of a system of 40 record perforations which readily lends itself to the keeping of records on a plurality of fields of a record sheet or card.

Other objects of the present invention reside in the provision of means for controlling the transferring of records, first, in 45 accordance with certain controlling characteristics of the record cards themselves, secondly, in accordance with the setting of certain controlling elements of the machine, and thirdly in accordance with the correspondence of the perforated card record 50 with the set up of the machine.

Another object of the present invention

resides in the provision of means for making a suitable designation upon the controlling 55 record of the transference to and the making of duplicated records.

A further object of the present invention resides in the provision of a machine for automatically making out notices in accordance with the controlling perforations 60 of master cards, suppressing the making of notices under certain conditions and for making the special designating records under other conditions.

While the machine herein illustrated and described is particularly adaptable for the making of insurance notices or bills from master card records containing data relative to individual policies it is to be understood that in its broad aspects the machine and the invention are not limited to such a particular use but are of general application in many other uses and for other purposes and particularly where notices, bills 70 or like cards or sheet data is to be made out in accordance with a series of successive individual perforated records.

Further objects of the present invention will be hereinafter pointed out in the accompanying specification and claims and shown in the drawings which show by way of illustration what I now consider as a preferred embodiment of my invention.

In the drawings,

Fig. 1 is a view of the complete machine.

Fig. 2 shows the master card with its completed perforations and printed designations.

Fig. 3 is a portion of the master card 90 perforated to designate an annual payment.

Fig. 4 is a similar section of the master card perforated to designate a monthly payment.

Fig. 5 is a section of the master card with 95 an equal number of notice-sent and posting perforations to designate that the policy holder has paid up his account in full and to indicate that such payment is properly perforated.

Fig. 6 is a section of the master card with 100 perforations designating a prepaid status of the account.

Fig. 7 is a section of the master card showing an open item or lapsed condition. 105

Fig. 8 is a diagrammatic figure showing

the system of combination hole perforations for the cards.

Fig. 9 is a view of the notice card which is printed and perforated in this machine. Fig. 10 is a diagrammatic view showing the sequence of operations performed by the machine.

Fig. 11 is a detail view of driving device in the base of the machine, the section being taken on line 11-11 of Fig. 21.

Fig. 11^a is a further detail view of the driving devices, taken on line 11^a-11^a of Fig. 21.

Fig. 12 is a further detail of the driving gearing beneath the base of the machine taken substantially on line 12-12 of Fig. 11.

Figs. 13 and 13^a are detail views showing gear box together with the worm gearing and one revolution clip therein.

Fig. 14 is a front elevation view of the master card section of the machine showing the master card storage magazine, the shuttle or card carriage and the discharge magazine for the master cards.

Fig. 15 is a top plan view of the master card storage and discharge magazines together with the master card shuttle and clip carriage.

Fig. 16 is a front elevation of the operating mechanism for one of the clip devices on the master card shuttle of the clip carriage.

Fig. 17 is a top view of the clip device with some of the parts broken away showing the clip device in open position preparatory to receiving a card.

Fig. 18 is an additional detail view of the clip device showing the clips closed and engaging the cards and with the non-jam device closed and in non-effective position.

Fig. 19 is a detail view of the non-jam device showing the cards stripped from the clips and the non-jam device operating to stop the operation of the machine.

Fig. 20 is a view of the clip device showing them swung back out of the path of the cards preparatory to the retraction of the clip shuttle.

Fig. 21 is a side view of one of the controlling cam shafts in the base of the machine with the base broken away to show the parts inside thereof.

Fig. 21^a is a side elevation of the right hand side of the machine with portions of the frame broken away to show the interior construction.

Fig. 22 is a sectional view of the vertical master card carriage section, being taken on line 22-22 of Fig. 24.

Fig. 23 is a side elevation of the master card vertical carriage.

Fig. 24 is a front elevation of the master card vertical carriage with the driving connections for same.

Fig. 25 is a top plan view of the master card reading pins showing the transfer shafts to the dummy pins for controlling the printing and perforating of the stub on the notice card. Certain parts are shown in section.

Fig. 26 is a front elevation of the notice card section of the machine showing the storage and discharge magazine for the notice card, the notice card shuttle and certain of the controlling and driving cams.

Fig. 27 is a top plan view of the notice card section of the machine showing the storage magazine, the notice card shuttle or clip carriage and the discharge magazine. This view also shows in plan the type carriers for printing upon the notice card.

Fig. 28 is a vertical elevation of the notice card vertical carriage.

Fig. 29 is a side elevation of the same.

Fig. 30 is a vertical section of the notice card vertical carriage section being taken on line 30-30 of Fig. 28.

Fig. 31 is a vertical transverse sectional view of the machine showing the reading pins for the master card and the type carriers and printing devices for printing upon the body portion of the notice card. This view shows the parts in their normal home position.

Fig. 32 is a front view of the zone finding reading pins and notice and posting pins with associated operating devices. This view is substantially a section taken on line 32-32 of Fig. 33 looking in the direction of the arrows.

Fig. 33 is a sectional view taken on substantially line 33-33 of Fig. 32 and showing the annual zone finding pins and the posting pins with associated controlling devices.

Fig. 34 is a rear view of the parts shown in Fig. 33.

Fig. 35 is a detail view showing the annual pins advanced with the annual combs moved into cooperation therewith to determine the annual zone on which the machine is to operate.

Fig. 36 shows the notice-to-be-sent controlling device in a moved position in which one of the notice-to-be-sent pins is projected and has permitted the sending of a notice.

Fig. 37 shows the same parts in another condition in which no parts are advanced.

Fig. 37^a shows a detail of the means for suppressing the operation of all but one of the notice-to-be-sent pins.

Fig. 38 is a side view of the controlling members mounted upon the frame which carries the zone-finding, notice-sent, and posting pins, looking from the left.

Fig. 39 is a similar view of the controlling parts mounted upon the same frame and looking from the right.

Fig. 40 shows the condition of the controlling parts corresponding to card conditions as indicated in Fig. 5.

Fig. 41 shows a similar condition corresponding with Fig. 6.

Fig. 42 shows a condition when a card perforated as in Fig. 7 passes through the machine.

Fig. 43 is a side view of the frame carrying the feeler bars and showing the means for operating the same.

Fig. 44 is a front view shown in Fig. 43. The lower part of this figure is broken away to show the cross comb construction.

Fig. 45 is a horizontal section showing the selecting dummy punches for controlling the punching of a notice-sent perforation in accordance with any particular month.

Fig. 46 is a side elevation of the frame carrying the reading pins and the notice-sent punches.

Fig. 47 is a front elevation of the reading pin and punch section of the machine.

Figs. 48 and 49 are diagrammatic views showing the means for selecting the notice-sent punches.

Fig. 49^a is a detail of the controlling disk for controlling the printing and perforating of the monthly designations on the stub of the notice card.

Fig. 50 is an enlarged detail sectional view showing the feeler pins in normal position and factoring feeler bars and vertical combs which are controlled in accordance with combination of positions taken by the pins. This view also shows the type carriers which are differentially controlled by the feeler bars.

Fig. 50^a is an enlarged detail of one of the feeler or reading pins, and shows its connections to a pin bar.

Figs. 51, 52 and 52^a show moved positions of the pin bars and the vertical combs controlled thereby. These views show the means for selecting combination of positions of the vertical combs in accordance with the combination of feeler pins which are advanced through perforations in the card.

Figs. 53 to 56, inclusive, show diagrammatically the means for taking off readings in the vertical combs from various combinations of positions by means of the feeler bars and for placing such reading upon a corresponding type carrier.

Fig. 57 is a view similar to Fig. 50 with the parts in moved position which they assume upon the printing of the letter V.

Figs. 57^a and 57^b are perspective details of the vertical combs with their cooperating feeler bars; Fig. 57^a showing the parts in normal home position and Fig. 57^b showing the parts in displaced position. The particular section of the combs herein illustrated is the part which controls the printing of letter V.

Fig. 58 is a front detail view showing the controlling bails for the type carriers and punch carriers in the notice section of the machine.

Fig. 59 is a vertical sectional view of the type carriers, the vertical combs, punches and dummy pins which are utilized to print and perforate upon the stub portion of the notice card.

Fig. 60 is an enlarged detail view of one of the type carriers and shows in detail the means for operating the punches for perforating the code system of perforations upon the stub portion of the notice card.

Fig. 61 is a diagrammatic view for showing the system for obtaining code perforations by the punches.

Fig. 62 is a detail side elevation of the left hand side of the machine and shows the punch and the type striking mechanism together with certain controlling cams for effecting movement of the type carriers and like parts.

Fig. 63 is an enlarged detail view of the cross comb device for storing a reading of the vertical combs which control the printing upon the body portion of the notice. These cross comb devices are adapted to transfer the reading to the vertical combs controlling the printing and perforating upon the stub portion of the notice.

Fig. 64 is a view of the cross combs in the position which they assume when reading the vertical combs.

Fig. 64^a is a similar view of the cross combs showing them in the position assumed when transferring the reading to the vertical combs which control the operations upon the stub.

Figs. 65 to 67, inclusive, are diagrammatic views illustrating the cross comb operation.

Fig. 68 is a sectional view taken on line 68—68 of Fig. 63.

Fig. 69 is a detail top plan view of the cross combs showing the position of the stepped abutment with respect to the depending tails on vertical combs.

Fig. 70 is a detail of certain operating parts for controlling type carrier bails.

Fig. 71 is a timing diagram of the machine.

For a clear understanding of the present invention a brief description will first be given of the master card which is operated upon by the machine and from which various data readings are taken. Thereafter the so-called data or notice card will be described and the steps of imprinting and perforating the data on this card will be set forth.

Referring to Fig. 2, 100 designates the so-called master card. This card is provided with a number of various fields containing printed data relating to insurance

or like information and corresponding to each printed field there is a perforated field with proper combinations of perforations to indicate corresponding numbers or letter characters. The upper field 101 of the card is further subdivided vertically into subfields so that the different data can be distinguished. The first subfield, for example, contains the number 3 designating that the policy was issued in March, the next subfield has the number 1 indicating March 1st, the following field giving the year. The remaining subfields designate post office number, policy number, premium, and number of payments per year. Corresponding to each of these subfields there are perforations disposed in combinations which are based upon the combination hole system set forth in Fig. 8 of the drawings.

As shown in this figure, there are provided in columnar arrangement six so-called hole spaces. The digits are perforated in the upper four hole spaces as shown, and the number of perforations to designate any particular digit in no case exceeds a maximum of two. Such perforations are variously disposed in the upper four hole spaces to designate by their combinations, number and position, the various digits. The alphabetical characters on the other hand are disposed over the entire six hole spaces, and as herein shown they comprise combinations of from one to a maximum of three.

It will be noted that this combination hole system is one in which the number of hole spaces (and the corresponding number of perforation-sensing or reading elements) to accommodate the various combination arrangements of perforations corresponding to the letters of the alphabet and to the various digits, is an absolute minimum. Referring to Fig. 8 it will be seen that at least thirty-four different combination arrangements of perforations are necessary to effect different and distinctive records for the various letters of the alphabet and the digits. An attempt to employ a maximum of five hole spaces to accomplish this result would fail, for the reason that the maximum possible number of combination arrangements of perforations in a five-space field is thirty-one. While this number would suffice for the alphabet it would not suffice for both the alphabet and digits. By employing six hole spaces sixty-three different combination arrangements of perforations may be obtained. This is amply sufficient to provide a distinctive record for each of the letters of the alphabet and for the various digits and, if desired, other distinctive records may be employed, to designate punctuation marks etc., well within the possible limit of combination arrangements of holes. For example, as shown in Fig. 8, one of the

combination arrangements corresponds to a period (.)

It should be noted further that not only is the system one which utilizes the minimum number of hole spaces required for the accommodation of the thirty-four or more different characters, but also one which employs the minimum number of perforations to represent the various characters. To explain this more fully attention is called to the fact that in accordance with the invention (see Fig. 8) all of the six possible combination arrangements of single perforations are utilized. Thus the characters E, O, 1, 2, 5, and . are each represented by a single perforation, each of such single perforations being located in a different hole space than that in which any other is located. The system also utilizes all of the possible combination arrangements of two perforations. The characters R, A, P, U, Y, T, W, Q, H, 3, 4, 6, 7, 8 and 9 are each represented by two perforations in different combination arrangements. This utilizes all fifteen of the possible combination arrangements of two perforations. The remainder of the characters, i. e., in the present case the characters Z, X, S, C, V, B, N, G, M, L, K, J, D, F, are each represented by three perforations in different combination arrangements. Thus all of the one perforation combination arrangements, all of the two perforation combinations, and some of the three perforation combinations, are utilized.

In addition the various combinations are preferably so selected as to utilize the single perforations to represent characters which are most likely to occur most repeatedly in the particular service in which the system is employed (see for example the letter E), and the two hole arrangements to represent characters which are next in order in their frequency of occurrence.

By virtue of these features, described above in connection with the hole spaces and combination arrangements, the card-space required to accommodate the desired information is minimized, the labor in punching is minimized, and the wear upon the perforation-sensing or reading elements and connected parts is greatly reduced.

It will be understood that the perforating and printing of the initial record upon the master card 100 is performed in a separate device which does not form the subject matter of the present application. Disposed below the field 101 is a perforated field 102 which contains the so-called numerical hole perforations. Below this field 102 is provided field 103 upon which may be printed the name of the holder of the policy. Below the printed field 103 is a hole space field 104 which contains the perforations corresponding with the alphabetical char-

acters making up the name of the policy holder. Fields 105 and 106 designate by printed characters and perforations respectively the street address, and fields 107 and 5 108 correspondingly designate the town and state. Disposed below field 108 there is a dividing line and below this dividing line there is a field in which perforations may be placed denoting the month in which a 10 notice is to be sent to the policy holder. As illustrated in Fig. 2 the months of January, April, July and October are punched out as indicated at 109. These punchings predetermine the sending of a notice on 15 these particular months.

This particular portion of the card contains a plurality of these fields, four being here shown disposed side by side and corresponding to four years. It may be explained 20 that where the notice is to be sent quarterly as with the card of Fig. 2, the perforations of 109 are not repeated for the succeeding months and year fields after the first. These particular holes in the first 25 monthly field determine the sending of a notice for the entire four years which is the capacity of the particular card herein shown. The monthly fields 110 are also adapted to receive certain perforated data 30 during the operation of this particular machine as will be hereinafter explained. Other space is also provided for receiving perforations placed therein by another machine to denote the payment of the various 35 policies. Disposed below the monthly notice fields 110 is a printed zone field 111 with a corresponding perforated field 112. These fields are subdivided to receive printed and 40 perforated data indicative of successive years such as 21, 22, 23 and 24 and also contain miscellaneous data relating to month and year of birth of the policy holder. Disposed below field 112 is a portion 45 of the card which contains only printed data with a suitable blank space for receiving 50 written records. These particular fields on the card relate to the insurance system, and inasmuch as they are in no way controlling upon the operation of the machine they need not be described.

Returning now to monthly notice field 110, perforations 114 designate that a notice has been sent out by the machine. With the card illustrated it will be seen that 55 notices has been sent out for all of the quarterly months of 1921 and for the first three quarters of 1922. The perforation opposite the word Oc. designating October is shown in dotted lines and this indicates 60 the status of the card after the mailing of the October notice. If no October notice had been sent there would be no perforation as shown at this point. Adjoining the notice-sent perforation column 114, and to 65 the right thereof, is a column 115. The per-

forations in this column designate that the payment has been received for the particular months in which the notice has been sent. The absence of a perforation at this point opposite any corresponding perforation 70 114 in the notice-sent column designates that although a notice has been sent a payment has not been received, or at least has not been posted by the posting machine. 75

It will be understood that the arrangement of perforations in the monthly notice-to-be-sent fields can be otherwise arranged. In Fig. 3 for example, a perforation 109^a is shown designating an annual payment. Fig. 4 designates the method of perforating the 80 monthly field 110 if notices are to be sent out monthly. Here a single perforation 109^b is provided in the third printed month column. Such a perforation occurring at this point will cause the machine to automatically issue a notice at each month when the master card is passed in the machine. Fig. 5 designates a condition in which notices are to be sent monthly and in which the policy holder has fully paid up his 85 premiums to the date of issue of the last notice on April, 1921. This last fact is indicated by an equal number of perforations 114 and 115. Fig. 6 designates a different condition of payments in which the policy 90 holder has paid in advance for a period of three months. This condition is designated by the three perforations 115 in the posting column running up to a higher position 114 in the notice-sent column. As here indicated 95 the policy holder has paid his premiums in full up to October, 1921, whereas the notice-sent column designates that the machine is to send its next notice on August of 1921. If a master card as perforated in Fig. 6 is 100 passed through the machine, no notice will be sent until the notice-sent perforations 114 catch up and align with the payment perforations 115. It will be understood, however, 105 that the perforation 114 will be made each 110 month as the master card is passed through the machine.

Fig. 7 indicates a so-called open item of lapse condition. Here there is no paid or posting perforation 115 opposite the uppermost notice-sent perforation 114 and this designates that the last due payment has not been received.

Fig. 9: The notice or data receiving card here shown comprises a main portion 116 and a stub portion 117. The main portion has thereon printed data derived from field 101 relating to policy number, premium due, and number of payments a year. Upon the succeeding lines there are placed printed data corresponding to fields 105 and 107 on the master card. This printed data in the aggregate gives the full name and address of the policy holder. On the stub portion 120 of the notice there is provided a printed 125 130

field 118 and corresponding perforated field 119. These two fields, respectively, designate by printed impressions and perforations the policy number and the month of mailing of the notice. A further subdivision of field 118 provides a space or field 120 in which a lapse notice may be marked upon the card. It will be understood that there is a corresponding perforation field 10 designating this lapse.

A space below field 118 is a further field 121 having a corresponding perforated field 122 below field 119. These two fields, respectively, receive printed and perforated numbers of the policy numbers, and the amount of the premium.

The general operation of the machine can be best understood from diagram Fig. 10. In this figure the master cards are shown in their successive positions which they assume in relation to the various reading devices in the form of feeling pins and punching devices which punch the perforations 114. The first operation on the card takes place when it is in the lower position. The first reading operation of the machine upon the master card is for the purpose of reading the field 112 and comparing this reading with the year in which the machine is operating to prepare notices. If correspondence exists between perforated field 112 with the yearly set up of the machine suitable pins 124 which cooperate with the field 112 control certain devices which allow the punching of a notice-sent designation upon the master card and also indirectly control the printing and perforating of the notice card. If a card having no annual zone in agreement with the annual set up of the machine is presented to the pins 124, printing and perforating on the notice card is suppressed, a blank card is issued and the perforating of the notice-sent designation upon the master card is suppressed. Concurrently with the reading of the field 112 fields 109 are sensed by a group of pins 125 and if any perforation in the fields 109 and 109^b correspond with a set up of the machine for the current month the machine is permitted to send out a notice properly filled out. For clearness here the machine is shown with an April pin projecting. Otherwise printing and perforating of the notice card will be suppressed and a blank card issued. At the same time that the last mentioned field is sensed the machine senses field 114 by means of pin group 126 and sets up a control for the perforating of the succeeding notice-sent designation 114. This actual perforation is performed in a later cycle of the machine. Concurrently a pin group 127 senses the perforation field 115 and determines the payment status of the particular policy holder. If the policy is 65 overdue a suitable lapsed payment demarca-

tion will be made upon the stub of the notice card.

While the master card is still in lowermost position a suitable group of pins 128 are presented to the field 102 of the card 100 and these pins by their advance through the perforation of field 102 determine the position of suitable type carriers which imprint the amounts 256, 14.90 and 4 upon the amount body portion 116 of the notice card. Concurrently 256 is printed on field 118 of the stub portion and corresponding perforations designating 256 are made in field 119. During this operation the month 10 is also printed in its proper subdivision of field 118 and corresponding perforations are placed in field 119. The printing of this number 10 and the controlling of the punches is determined by a setting of the machine and not by any perforations upon the master card. Concurrently with the reading of field 102 by pin group 128 certain pins of the 128 group take a reading of the amounts 3 and 14.90 from the field 102, transfer these amounts to suitable storage devices from which type carriers and punches for imprinting and perforating fields 121 and 122 are controlled at a later cycle of the machine operation. At the time of printing field 118 with the characters 10 and 256 the lapse field 120 will be printed with a character indicating a lapsed payment if the particular policy holder omitted to make payment upon the previous notice.

The next step in the cycle is to advance the card 100 in the next higher position to present field 104 to the pin group 128. These pins then advance and control the operation of the type carrier members and the printing of the policy holder's name on the body portion of the notice.

The next operation is to again raise the card 100 to present the field 106 to the pin group 128 and control the printing of the street address upon the body portion of the notice. Concurrently with the recording of the street address under the control of the pins 128, the type carriers operating upon the stub of the notice again come into action and take a reading from the storage devices and imprint and perforate the numbers 3 and 14.90 on the respective fields 121 and 122 of the stub.

The master card is again raised to present the pins 128 to perforated field 108 of the card. The advancing pins at this time control the printing of the town and the State upon the fourth and last line of the body portion of the notice. While the card is in this position a group of punches 129 are presented in alignment with the notice-sent fields 114 of the master card and one of these punches is properly operated to perforate the master card and indicate by such perforation that a notice has been sent. Such perfora-

tion is shown directly beside the letters Oc. representing October in the master card as shown in Fig. 2. For clearness in illustration in Fig. 10 the April punch is shown as 5 operating.

In general the machine may be stated as comprising a master card feeding section which is adapted to take the master cards one by one from a storage stack, feed the 10 same into the machine to a first sensing station. In this position the cards are received in a carriage which is adapted to move vertically to present the successive fields of the cards to the various sensing pins and 15 punches. After the last field of the card is thus sensed and the notice-sent perforation is punched in the card, the carriage returns downwardly to its initial position. The card is then gripped and moved to a second or 20 inactive station and at a succeeding cycle is taken from this station and placed in a discharge stack. The notice card section of the machine is in many respects similar to the master card section. It comprises a storage 25 stack from which cards are advanced by a picker into a suitable grip mechanism which advances the cards to an initial printing position. Here again a carriage receives the cards and successively moves them in a 30 vertical direction to present the successive lines to the printing and perforating members. After the last printing is completed the carriage is returned downwardly, the 35 perforated and punched notice card is gripped, and the card is advanced into the discharge stack.

Machine drive.

Below the base of the machine as shown in Fig. 11 is an electric motor 130 which is connected to the supply main by means of a switch 131. Motor 130 by belt and pulley drives a shaft 132 which extends into a gear box 133 (see Figs. 12 and 13). Within the 40 gear box there is a worm reduction 134 which through a suitable one revolution clutch 135, Fig. 13, is adapted to impart rotation to a shaft 136 carrying bevel gear 137. The engagement of the clutch 135 is controlled through a shaft 138 from start and 45 stop keys 139 and 140, Fig. 11, which control the one revolution clutch through toggle linkage 141. Link 142 extends to and connects with a link 143 which extends to a non-jam device to stop the operation of the 50 machine if cards are not fed properly.

From gear 137, Fig. 12, the drive is effected to a shaft 146 which through gearing 147 drives the cam shaft 148. This is the main 55 cam shaft of the machine. Also mounted on shaft 146 is a crank arm 149, Fig. 11, which through a suitable linkage rocks a stud shaft 150 mounted in a bracket on the sub-base of the machine and carrying an 60 arm 151 which drives the clip master card

carriage. 152 is the picker actuating arm which is driven through link or strap 156 from an eccentric 155 on shaft 148 (Fig. 11). Arm 152 carries the usual card picker 153 (Figs. 14 and 15) which is adapted to advance one master card at a time from a storage stack 154 through a suitable controlling throat in the side of the magazine into a position where the leading edge of the card may be gripped by gripping devices, as will 70 be hereinafter described.

The clip carriage makes a multiple number of strokes relatively to the picker movement to secure a rapid card feed. The clip carriage makes six strokes to one of the 80 picker but for purposes of description these idle strokes may be disregarded. This multiple clip carriage movement also takes place with the notice card feeding devices.

The master card clip carriage comprises a 85 frame member 157 which is slidably mounted for horizontal movement upon suitable guide rods 158. The carriage is actuated in its back and forth movements by the linkage 151—159. As shown in Fig. 15 the master card 100 is gripped by a device which 90 comprises grippers 160. These grippers are mounted on stud shafts or studs carried by the frame of the carriage 157. Grippers 160 upon the first shifting movement of the carriage transfer the card to the position indicated at A' in Fig. 15 and by dotted lines in Fig. 14. Thereafter the card remains in this relative horizontal position and is moved vertically through a series of steps and then 100 returned downwardly, as will be hereinafter explained. Grippers 160 have now become disengaged from the card and thereafter return with the carriage to the extreme left hand position to grip a new card emerging 105 from the storage magazine 154. Concurrently with such engagement with the following card the second pair of upper and lower grippers 161 engage the upper and lower edges of the card which is in the A' position 110 and upon the movement of the carriage to the right transfer the card to the position indicated at B', Figs. 14 and 15. The card is then released or stripped from its gripper, the carriage returns to the left and the 115 pair of grippers 162 then engage the leading edge of the card in the B' position and transfer it to the discharge magazine 163, see Fig. 15. All of the grippers 160, 161 and 162 operate in unison. A suitable cross-linkage 164 is provided to effect the joint operation of the grippers.

Grippers 160, 161 and 162 are essentially alike in their operating characteristics and only one set will be described. Referring 125 now to Fig. 17 the portion 157 of the carriage frame forms a shoe for the advancing card and is provided with suitable rock shafts 172. Fixedly mounted on shaft 172 is a jaw clip 170 and rotatably mounted

thereon is an anvil clip 171. These clips have tails 173—174 which are interconnected by springs 175. There is also provided a non-jam member 176 which is rotatably mounted upon shaft 172 and disposed adjacent the anvil clip 171. This non-jam member is provided with a spring 177 which is connected to the tail 174 of clip 170. The finger 230 is pivoted on an extension of anvil clip 171 and has its nose bearing against a cam edge on the non-jam member 176. The opposite end of the finger 230 is provided with a finger 231 bearing against the tail 174. The purpose of the finger piece 230 is to restore the non-jam member 176 to the position shown in Fig. 17 on the opening of the clip jaw 170. Fig. 17 shows the grippers in open position preparatory to receiving a card. To open the grippers a cam member 178 is pivotally mounted upon a fixed plate 179 supported on fixed frame 180 (see Fig. 16). Fixed to the upper end of the clip shaft 172 is a bell crank 181 having a roller cooperating with cam 178. Cam 178 is rocked counterclockwise at the proper time in the operation of the machine by means of a bell crank 182, Fig. 16, which bell crank is operated by a link 166 extending downwardly into the base of the machine and connected with a pivoted lever 167 which in turn is actuated by a cam 168 on shaft 148 (see Figs. 14 and 21). Upon drawing down link 166 cam 178 is rocked counterclockwise until latched by latch 184 to which the cam return spring 183 is connected. By the above operation the clip shaft 172 is rocked clockwise swinging the clip jaw 170 in like direction. The clip anvil 171 is rocked clockwise until arrested by the contacting engagement of its tail with a block 185 which is carried on the shoe member 157. After such engagement 171 remains stationary and 170 moves further to the open position shown.

The clip is now ready to receive the card. When the card picker has advanced the cards into the jaws of the clip the latter are tripped by rocking latch 184 counterclockwise. Such movement is secured through a rock shaft 186 (Figs. 14 and 17) which is actuated at the proper time in the cycle by means of a linkage and bell crank 187 which cooperates with a trip member 188 (see Fig. 21). As heretofore explained the various clip devices are inter-connected by linkages 164 and by controlling the opening and closing of two clips 160 all of the other clips will be similarly controlled.

It may be here explained that the opening of the various clips is only effected prior to the receiving of a card and this opening movement is not utilized for disengaging or releasing the card from the clip carriage.

Fig. 18 shows a pair of clips 170—171

closed and properly engaging the card so as to advance the same upon the movement of the clip carriage. In this figure it will be noted that the non-jam member 176 has abutted against the card 100. The purpose of this non-jam member is to interrupt the operation of the machine should a card not properly engage the clips or be stripped therefrom at improper times in the machine cycle. If such a non-jam device be not provided the cards would pile up in the card feeding device and be mutilated and possibly damage portions of the machine. During proper card operation, the non-jam member allows the continued operation of the machine. It only becomes effective when the cards become released improperly from the clips. As shown in Fig. 18, non-jam member 176 is provided with a tail carrying a lug 187* which under the conditions shown is out of engagement with a notch 188* in the locking bar 189. The locking bar 189 extends across the entire clip carriage projecting beyond its right end as shown in Fig. 14. The locking bar is normally drawn to the right by a spring 190 and upon the extreme movement of the locking bar carriage the end of the locking bar is adapted to yield upon contact with a T-piece 191, Fig. 14, which is pivoted upon the frame and connected to a link 143 heretofore described. Under these conditions with the locking bar 189 unlatched the machine will continue to operate. If, however, the lug 187* has engaged in the notch 188* of the locking bar under the stripped card condition as shown in Fig. 19 the spring 192, Fig. 14, on the T-lever 191 will yield and the lever 143 will be drawn upwardly interrupting the operation of the machine. After the clip carriage has moved to the right it is necessary that the clip carriage may be returned to the left without interfering with the cards. This clip condition is shown in Fig. 20. Such a clip condition is secured by means of an adjustable stop 193 mounted upon the end frame of the machine.

Just before the carriage has reached the extreme right hand end position the interconnecting link 164 will be in the position of engagement with a notch 196. Just before the end of the right hand movement an adjustable stud 193 will contact with latch 194 and release it to the position shown. Thereafter the spring 195 will draw the link 164 to the position shown and thereby swing the clip assembly 170—171 and 176 counterclockwise and out of the line of cards as indicated in Fig. 20.

It has been previously stated that the removal of the cards from the clips is effected by stripping the same therefrom. This stripping operation is effected at the time the card is advanced into the vertical

carriage at the so-called A' position. Referring now to Figs. 22 to 24 inclusive, the vertical card carriage comprises upper and lower slotted card guides 200 and 201 joined together by strips 202 which are guided by vertical movement by guides 203. Hinged to strips 202 are flipper plates 204 which are spring pressed outwardly as shown in Fig. 22. The advancing card 10 presses back the first of plates 204 and is arrested by the second plate at the right of Fig. 22. In this manner the card is stripped from the grippers at the A' position.

15 To advance the vertical card carriage in a vertical direction and to present successive fields on the cards to the reading pins a rack 205 is provided on the carriage intermeshing with a gear 206 which through 20 a small pinion and rack 207 is adapted to receive motion from a cam follower 208 operated by cam 209 (see Fig. 21). The configuration cam 209 is such as to present the 25 cards to the proper fields as indicated in diagrammatic Fig. 10. When the carriage has reached its extreme upper position a return spring 210 (Fig. 24) operates to return the carriage to lower position preparatory to the withdrawal of the card into 30 the B' position.

Before the card can be advanced into the B' position by the card grippers, the flipper card stop 204 on the right must be retracted. This is effected by means of a 35 presser member 211 (Fig. 25) actuated from shaft 212 by a bell crank lever and linkage 213 which extends into cooperation with a tripping member 214 (Fig. 21) on the cam shaft 148. Restoration of the 40 finger 211 to outer position is shown by means of a spring 215 (see Fig. 25).

When the cards are advanced from the A' to the B' position they are stripped from the grippers by means of a hinged plate 45 216 similar to plate 204 which plate is actuated by a finger 217 from shaft 212. There is also provided a spring catch 218 to prevent retrograde movement of the cards from B' toward A' position (see Fig. 25).

50 The foregoing has described the master card cycle through the machine.

The notice cards are handled in substantially similar manner to the master cards. Referring now to Figs. 26 and 27 the notice 55 cards are taken from a supply magazine 220 and advanced into an intermediate position for printing and perforating and are eventually discharged into storage magazine 221. With these notice cards there is no 60 intermediate B' position of the cards. They are advanced directly from the storage to a shuttle clip carriage which in its details is similar to the carriage previously described for the master card section of the 65 machine. This clip carriage is indicated

generally by character 222 in Fig. 27. The notice card section of the machine is provided with a non-jam linkage 223 which extends down and cooperates with a bell crank similar to 224 and on the same shaft with 70 it (see Fig. 11). The notice card clip carriage is actuated through a linkage 225 shown in Figs. 26, 21 and 11a. This linkage receives its drive from shaft 146 through the crank motion 226 and intermediate bell crank 227. 75

The notice card picker actuating arm 228 (Fig. 26) receives its drive from link and crank motion 229 operating on shaft 148 (see Fig. 11a).

80 The clip devices in their cycle details are similar to those heretofore described for the master card section. The set up and tripping device are slightly different. Referring to Fig. 27, shaft 236 is rocked to open the clips and the closure of the clips is controlled by trip-off lever 237 which in turn is controlled by a link 235. Shaft 236 is actuated from a knock-off cam 238 on shaft 148 through intermediate pivoted levers 239, Fig. 21. Link 235 is similarly actuated from 90 a knock-off member 240 on cam shaft 148. The vertical movement of the notice card carriage to effect printing and perforating on different fields and lines thereon is likewise controlled by cam 241 which operates 95 follower 242 which is directly mounted on the lower end of the card carriage.

100 It will be understood that for convenience in illustration the notice card section of the machine and the master card section of the machine have not been shown in their actual timed relation. In actual operation the master card machine section operates first to receive master cards and take readings therefrom. The notice card feeding 105 device operates at a later time in the cycle in order to receive the readings which have been taken from the master cards in the master card section. For convenience in illustration both the master card and notice card sections are shown in their extreme 110 left hand card receiving position.

115 Referring again to the diagram illustration Fig. 10, it will be seen that the notice card is printed upon a plurality of successive superimposed horizontal lines. This necessitates a vertical card carriage in the notice section of the machine. The notice cards passing from the storage section 220 are carried by the clip carriage 222 into a vertically 120 movable card carriage which is shown in Figs. 28, 29 and 30. The notice card 116 slides into slotted card guides 244 in the card carrier and is stripped from the grippers by means of a spring pressed flipper plate 245 (see Fig. 30). Retrograde movement of the card from the vertical carriage is prevented by means of a spring plate 246. The card carriage is guided for vertical movement in guides 249, Fig. 30, and is 130

elevated by a follower roller 242 which cooperates with a cam 241 upon cam shaft 148. The card carriage is provided with a fixed platen 252 to receive the imprints upon the body portion of the notice or data card. A platen 253 is provided for receiving the impressions of the type upon fields 118-121 of the stub portion of the card. This is a movable platen and is mounted upon the 10 clip carriage as shown in Fig. 26. After the card has been completely printed and perforated it is again grasped by the clip carriage and withdrawn to the right and delivered to the discharge stack. In order 15 to permit the discharge of the card 116 from the carriage the flipper plate 245 is released at the proper time in the operation of the machine by a cam member 255 on the right hand clip shaft 254 upon the rocking of the 20 same. This retracts the flipper 245 out of the path of the card and allows the card to be advanced by the clip carriage in its movement.

The foregoing description has explained 25 the passage of the notice or data card through the notice card section of the machine.

Perforation reading devices for master card perforations.

As heretofore explained the master card when in the so-called A' position first presents field 112 to reading pins 124 to take readings of the year from the perforations 35 in yearly fields 112 of master card 102. See diagrammatic Fig. 10.

The pin group 124 (Fig. 31) are the yearly zone finding pins. Pin groups 125, 126 and 127 are shown in Figs. 32 and 33. All 40 of these pins are slidably mounted in a frame 257 having suitable pin guiding portions, and are provided with the usual collar and compression advancing springs 258. The entire frame 257 and pin box assembly 45 is slidable back and forth on guides 259 on the base portion of the machine. This movement is effected through links and levers 260 connected to shaft 261 which has an arm 261^a rocked by a cam 261^a on shaft 262 50 (Figs. 21, 21^a and 62). The drive for the shaft 262 is secured in the following manner from the base drive of the machine. Shaft 262 is provided with a gear 263 meshing with a gear 264 on shaft 265. Shaft 265 is 55 driven by gearing 266, 267 meshing with a gear 268 in the gear box in the base of the machine (Figs. 13 and 13^a). The drive is such that at each card cycle the pin box assembly is advanced and retracted once. By 60 the advance of the pin box assembly when permitted such combination of pins 124 as encounter perforations of the card will advance through the card. On such of the pins as had not encountered perforations springs

258 will yield and allow certain pins to remain in unadvanced position. On the stub ends of pins 124 there are certain lugs 270 (see Figs. 33 and 35). These lugs cooperate with annual comb plates 271 which are stepped to correspond with a particular year 65 in which the machine is operating. These annual comb plates are removable and are removed from the machine at the end of a year and a new set with proper comb slots 70 inserted for the following year. From the card diagram Fig. 2 it will be seen that there are eight annual pins for each year and there are therefore two comb plates 271 for each year. The annual comb plates 271 of which there are four pairs in the machine 75 move upwardly after bail 313 is elevated, under the influence of springs 273 which are connected to bell cranks 274 which in turn are connected to the comb plates by plates 272. This initial movement takes place irrespective of the correspondence of the notches in the comb plates with lugs 270. This initial movement permits the rocking of bell 80 crank levers 274 in a counterclockwise direction and permits the advance of the corresponding notice-sent pins 126 and payment status pins 127 for the corresponding year. Bell cranks 274 also on their restoring movement restore pins 126 and 127. Fig. 34 85 shows four plates 272 each connected to a pair of yearly combs 271. To each of the plates 271 there is connected one bell crank 274 and to this bell crank 274 supplementary crank arms 274^a are connected by pins 275 (see Fig. 32). These supplemental arms 90 100 105 110 115 120 125 126 127 128 129 130 131 132 133 134 135 136 137 138 139 140 141 142 143 144 145 146 147 148 149 150 151 152 153 154 155 156 157 158 159 160 161 162 Monthly notice-to-be-sent pin reading control.

As heretofore explained, pin group 125 5 cooperates with perforations 109 or 109^a to determine whether a notice is to be sent or not. If any one of the pins in these notice-to-be-sent columns advance through a perforation in the card the machine is to send 10 a notice. It is therefore necessary to obstruct the pin openings for months other than the ones in which the machine is operating. For this purpose all of the openings 109 for pins passing through card perforations are plugged by screws 276 which 15 are inserted in threaded pin openings in the backing plate 345 (see Figs. 37^a and 33). In these figures it will be noted that no screw 276 is provided for opening 278 which 20 is opposite the October perforation in the notice-to-be-sent fields 109 of the master card. Consequently, a pin in the 125 group advances and causes a notice to be made out. The control for suppressing the making out 25 of a notice will now be described.

Referring to Figs. 32, 33, 36 and 37 overlying all of the columns of pins 125, 126 and 127 are arms 278, 279 and 279^a. The latter arms 279^a and 279 overlie pin columns 126 30 and 127 and arms 278 overlie the notice-to-be-sent pins 125. These arms 278 and 279 have tail pieces which depend into contact with lugs 280^a carried on the rearwardly extending ends of the pins. Arms 278, 279 and 279^a are normally held in the position shown 35 in Fig. 33 by a bail 281 which is fixed on shaft 282. This shaft is rocked by a linkage 282^a, Fig. 39, which connects to a lever 282^b cooperating with a suitable cam 282^c on shaft 265 (Figs. 62, 31 and 26). Upon the lowering of bail 281 arms 278, 279 and 279^a 40 are permitted to drop until arrested by a lug 280^a on a forwardly advancing pin. If none of the pins 125 have advanced arms 278 of which there are three tied together 45 by a stud 278^a will drop all the way causing a pin 288 carried by a tail on the arm 278 to descend all the way in a slot in a link 289 and draw down the link to rock a bail 290 fixedly mounted on shaft 280. This condition of parts is shown in Fig. 37. The shaft 280 extends to a controlling unit 50 shown in Fig. 38. The shaft here carries a latching lever 283 which on the rocking 55 of the shaft 280 is thrown in the path of a member 284 slidably mounted in an arm member 285 fixed to the sliding frame 257. The shaft 280 and lever 283 are mounted 60 upon the sliding frame 257 so that upon the movement of the frame 257 to the right relatively to the base of the machine, finger 283 will engage the slide 284 rocking lever 286, which is pivoted to the base of the machine, clockwise, drawing link 287 to the left, swinging locking bail 291 into engage-

ment with the type and punch carrying bars in the notice writing section of the machine (see Fig. 31). By this means the printing and perforating of the notice is suppressed if none of the notice sent pins 125 have advanced. This condition of pin parts and levers 278 is shown in Fig. 37. It is also necessary to prevent the perforating of a notice-sent designation on the master card under the foregoing conditions. Such control is secured in the following manner.

Referring to Fig. 39 the drop lever 278 carries a pin 295 which upon the dropping of lever 278 all the way is adapted to contact with a latch 296 carried upon a bail 298 to swing the latch into the path of a block 297 mounted on sliding carriage 257. On the movement of carriage 257 to the left the latch 296 will be displaced to the left, rocking bail 298 clockwise and unlatching 85 a punch actuating finger 299 from a pawl 300. Parts 299 and 300 are also shown in Fig. 31. The actuation of punches 129 for the notice-sent perforations of the master card will be hereafter explained. It is sufficient to here state that the punching action is suppressed when no pin 125 is advanced through the notice-sent perforation.

If one of the pins 125 is passed through a perforation in the master card it is necessary that a notice be made out. Such control of the machine is effected through the drop levers 278. If these drop levers encounter one of the lugs 280^a in their descent they are prevented from descending a full 100 distance and consequently bails 290 are not rocked (see Fig. 36) and therefore the suppressing latch 283 is retained in the position shown in Fig. 39 and the operation of the type bars and punches in the notice-sent section of the machine is not suppressed.

The other condition to be controlled by the drop levers 279 and 279^a is the comparison of the notice-sent perforations in the master card with the payment perforations 110 therein. Such control is effected through the drop levers 279 and 279^a Fig. 33. For each particular field there is one set of drop levers 279 which cooperate with the posting pins 127 and a corresponding drop lever 279^a 115 which cooperates with the pins 126 passing through the notice-sent perforations 114. Fig. 40 shows a comparison of pins 126 and 127 in which the same number of pins 126, 127 have passed through perforations in the 120 card. Under these conditions a notice is to be made out. To compare the positions of drop levers 279 and 279^a and allow the making out of a notice when they both drop equal distances, a pair of levers 305, 306 are 125 provided pivoted on lever 279 and having tail pieces 307 and 308 overlying the top and bottom of the next adjacent drop lever 279^a. The opposite ends of levers 305 and 306 cooperate respectively with bails 302 and 290 130

and if drop levers 279 and 279^a have descended equally as shown in Fig. 40 the left hand ends of these levers 305, 306 will not spread and consequently neither bail 290 nor 302 will be rocked. Under these conditions notices will be printed and perforated in the usual way. If, on the other hand, there is a lapsed condition indicated by the master card, drop lever 279 having descended further than its adjacent lever 279^a (see Fig. 41), the tail 307 will be held up by drop lever 279^a, thereby rocking bail 302 counterclockwise. However, under these conditions bail 290 will not be rocked. This counterclockwise rocking of bail 302 is adapted to effect printing of a lapsed notice on the notice card. Bail 302 is mounted upon a shaft 303 which as shown in Fig. 38 carries a latch 304 cooperating with a plate 309 slidably mounted upon member 285 and interconnected to an arm 310. Arm 310 upon being rocked in the direction shown by the arrow (Fig. 48), is adapted to displace a stop 312 which controls the printing of a proper lapsed indication upon the notice card. The above operation of the linkage 309 and 310 is effected upon the sliding of the carriage 257 to the left in the manner heretofore explained for the control of the no-notice-sent operation. The condition of drop levers just described is illustrated in Fig. 41.

Fig. 42 shows the third condition in which the master card has indicated a prepaid status. In this condition of parts the drop lever 279^a has dropped further than 279. Consequently, 308 will be depressed by 279^a (Figs. 33 and 42), thereby rocking bail 290 and suppressing the making out of a notice. Under these conditions there will be a posting up of a notice-sent perforation upon the master card and this is proper inasmuch as the policy holder has paid up in full and no notice is to be sent him until his advance payment has been caught up by the amounts due. Restoration of lever 311 is secured by rocking of bell crank 311^a by means of a pin 311^b on cam 383 which is on shaft 265.

The advance of the pins 124, 125, 126 and 127 has been explained as being effected by means of the compression springs 258. Such advance takes place upon the rocking of the bell cranks 274 and 274^a in a counterclockwise direction. At the proper time in the cycle all of the pins 124, 125, 126 and 127 are restored and this restoration movement is secured by means of a restoring bail 313, Fig. 33, which is actuated from rock shaft 314 (see Fig. 38) which in turn is actuated through a link 315 having a lost motion connection with a crank on shaft 316. Shaft 316 is rocked from cam 360 by follower 359^a (Figs. 21^a and 62). After the bail has been rocked to restore the pins the bail is latched down by a spring latch 317 (Fig. 38) which is pivoted upon the frame and released upon

the advancing movement of the carriage 257 to permit the elevation of the bail by springs 318.

Although as heretofore explained the actual operation of punches 129 is effected at a later operation in the cycle than the reading of fields 109, 112, 114 and 115 of the master card the reading of the field 112 sets up a control for the punches and this control will now be described.

The purpose of punches 129 is to perforate the notice-sent designations in field 114. This punching is controlled conjointly by the yearly pins 124 and the notice-sent pins 127 and 126 as shown in the diagram. Referring now to Figs. 33 and 34, connected to one of the arms 274, 274^a of each annual group is a rearwardly extending portion to which there is connected by a lost motion pin and slot connection an upstanding arm 319. There are four of these arms 319, one for each pair of yearly combs 271. Arms 319 extend adjacent the rear of punch operating fingers 299. As shown in Fig. 45 there are four pairs of these fingers 299. Fixed on shaft 321 are four plates 322 to which spring latches 300 are pivoted. These latter latches are connected to the respective arms 319 and upon the raising of any individual arm its corresponding latch 300 will engage the pin 320 which connects each pair of punch fingers 299 to first swing the same forward and afterwards latch the same in the notch in latch 300. By this means the particular punch group of punches 129 is selected to operate in accordance with the annual live zone in the master card. It may be here explained that the actual punch operation is effected by rocking shafts 321, which through plates 322, latch 300 and pin 320 swings the selected pair of fingers 299 forward to operate the punches. Punch operating shaft 321 is operated through a linkage 323 which extends downwardly and has a rocker in contact with the cam 324 on cam shaft 262 (Figs. 26 and 62).

The mechanism just described selects a particular pair of rows including the punches in two adjacent columns. From these 12 punches there must now be selected for operation a single punch corresponding to the month in which the machine is operating in sending out notices. This control is secured by a manual set up in the machine. Referring to Figs. 25, 45 and 46, an index wheel 325 carries suitable symbols designating the months. The operator aligns the proper month designation on this wheel with an index and thereby displaces a rack 326 which is geared with the wheel to a position to correspond to the particular month. The rack 326 is fixedly mounted on the guiding rails 327 which are slidably mounted on end guides 328 (see Fig. 45). Frame 327 carries a group of dummy pins 330 which

are arranged in the frame in the manner shown in Fig. 48. Punches 129 for each year are arranged in two adjacent columns and fingers 299 for each year are spaced at less distances apart than the punches 129. By shifting shaft 331 on which the fingers 299 are mounted endwise either one or the other of the fingers may be brought into alignment with one of the punch columns 129. The dummy pins 330 are spring mounted in the carriage 327 and are arranged in staggered relation as shown in Fig. 48. By shifting the carriage 327 step by step endwise first the lowermost punch 129 is brought in alignment with finger 299, then the second, and so on. Upon the forward movement of the pair of fingers 299 the selected dummy pin will move forward and force the corresponding punch 129 through the master card at the proper position. After six spaces of the carriage advance have taken place a cam slot 332 (Fig. 47) on the carriage swings a bell crank 333 and shifts shaft 331 endwise so as to bring the other punch finger into alignment with the other column of punches of dummy pins 330 and 129. With the condition of parts as shown in Fig. 49, finger 299 will be operating upon the fourth punch 129 from the bottom.

In further explanation it may be stated that punch finger *a* of pair 299 is adapted to operate for the first six months of the year and punch finger *b* for the second six months. The selection of the individual months is controlled manually by the carriage 327 and this carriage is set by the hand index.

There is one other manual set up on the machine which may be here described which relates to the set up to print the month impression on the stub of the notice. This set up device comprises an index wheel 340 (Fig. 47) having a window aperture 341 through which numbers corresponding to the months are adapted to show. Wheel 340 is set by hand, a suitable knob being provided, and this wheel through gearing displaces a rotatable plate 342 (Fig. 49a) which is provided with apertures corresponding to the different months of the year and in accordance with the combination hole system of the present machine to allow the advance of pins through the plate which correspond to the particular month for which the plate has been set. These pins have no cooperation whatsoever with the master card and when advanced pass through pin openings at 343, Fig. 47. They extend rearwardly and cooperate with printing and perforating controlling devices of the notice section of the machine.

As heretofore explained the actual punch operation takes place at the last operating

cycle on the master card when field 114 is 65 in alignment with field 129.

The foregoing has explained all of the operations which are controlled from fields 112, 114, 115, 109 and 109^b on the master card. The next operation to be described 70 is the operation taking place on field 102. With this description the selecting operation for the type carriers and perforating devices which take place during the operation on field 104, 106 and 108 will also be explained, inasmuch as the operation of the pins through the holes in the master card is always the same. This description will also explain the setting up of type carriers for 75 all reading cycles.

Referring to Fig. 8 the system of combinations is based upon six hole spaces disposed in a vertical column superimposed one above the other. The four upper spaces of 80 the six are used for numerical combinations and the entire six are used for alphabetical combinations. In taking off numerical readings only a maximum of two perforations are necessary. For alphabetical characters, on the other hand, the maximum of 90 three is utilized. The controlling of the setting up of type carriers or punches from a pin setting having the combination perforations shown in Fig. 8 is effected by 95 means of a multiple factoring mechanism.

In order to properly guide the pin groups 124, 125, 126 and 127 after they have passed through the card it is customary to provide a perforated anvil member 351. (See Fig. 31). After fields 112, 115, 109 109^a and 109^b 100 are read the various reading pins are withdrawn from the card and the card is elevated in the manner heretofore explained. During such elevation it is necessary to withdraw anvil 345 out of the path of the 105 card carriage in order to permit vertical upward movement of the same. This removal of the anvil is effected by mounting the anvil on the links which are pivoted upon shaft 346 as shown in Fig. 31. Interconnected with these links is a toggle linkage 347 having connected thereto a link 348 carrying a follower cooperating with cam 349, Fig. 21. This cam is adapted to withdraw the anvil 345 at the proper time in the cycle. 110 In Fig. 31, 128 designates the alphabetical and numerical pins. These pins 128 extend through pin guide 350, (Fig. 25) and are adapted to project through a suitable backing plate 351 and are provided with fixed 115 collars 352 which are pressed against the forward rail 353 of an actuating and restoring frame 354 (Fig. 25) by springs 356. The rear perforated plate 355 receives the thrust of suitable slidable collars on pins 120 128 and the collars 352 and pins are held in forward position by springs 356. The advance of the pins 128 into contact with the 125

master card is secured by sliding frame 354 forwardly, thereby allowing springs 356 to advance the pins which align with perforations in the card. Such forward movement of the frame 354 is secured by toggle levers 357 mounted upon the sides of the frame and having a link 358 extending to an arm 359 (Fig. 21^a) fixed to shaft 316 and having a follower 359^a (Fig. 62) cooperating with the cam 360 on shaft 265. The toggle is broken and pins are advanced by means of a spring 361 and the restoration of the pins and the retraction of frame 354 is effected by means of the cam 360. Pins 128 extend rearwardly from plate 355 (Fig. 50^a) and carry collars 362 against which compression springs 363 abut. Upon the rear ends of the pins 128 are slidable collars 364 and the pins 128 beyond collars 364 continue through and connect to a plug 366, which is behind a projecting lug on pin bar 365. This construction on the rear end pins of 128 permits the pin rods to be restored in the rearward direction prior to the restoration of the pin bars 365 in a similar direction.

Referring now to Fig. 50, it will be seen that the pin 128 which cooperates with the upper hole space is provided with a pin bar 365. The next lower pin cooperates with a pin bar 367. Referring to Fig. 51, pin bar 365 has superimposed upon it an auxiliary pin bar 368. This auxiliary pin bar carries a lug 369 to which retraction spring 370 is connected. Lug 369 extends in the path of pins 371 and 372 which are respectively mounted upon pin bars 365 and 367. Fig. 50 shows the normal position of the parts with no pins advanced. With this position a lug on a vertical comb 373 overlies the top of supplementary pin bar 368 and is held elevated thereby. Three combs 373 are provided. One cooperates with the upper pair of pin bars 365 and 367 and the others, respectively, cooperate with the lower pairs of pin bars. Referring now to Fig. 51, a condition is here shown where vertical comb 373 has descended one step. This is secured by drawing the lower pin bar 367 to the left thereby causing pin 372 to react against lug 369 and withdraw supplementary pin bar 368 to the left. Pin bar 365 under these conditions will remain in normal position and then arrest the comb plate 373, at one step of descent. This condition corresponds to a single perforation in the second hole space from the top of the card corresponding to the numeral 5. Another condition which the comb plate 373 may assume is indicated in Fig. 52. Here pin bar 365 has moved to the left and 367 has remained stationary. Pin 371 by contact with lug 369 will withdraw the supplementary pin bar 368 to the left, allowing the comb 373 to drop two steps. This condition corresponds to a perforation in the

upper hole space in the card corresponding with the letter or numeral O. Fig. 52^a shows a condition in which both pin bars 365 and 367 have been withdrawn, i. e., with two perforations in the card. Under this operation both pins 371 and 372 will contact with lug 369 withdrawing all of the pin bars from under the comb 373 and permitting the latter to descend three steps until arrested by plate stop 394. The descent of the combs 373 is aided by means of suitable springs 374. It will be understood that the operation of the combs for the next lower pairs of pin bars is the same as just described. There is one vertical comb 373 cooperating with the intermediate pin bar group and one vertical comb 373 cooperating with the lower pin bar group. By the above means various set-ups of pin bars are secured, each set up being determined by the position and number of perforations in the card. For the sake of clarity and conciseness I shall hereafter refer to the various grouping of holes and hole spaces used to designate a character or numeral, as a combinational hole system. The pin bars 365, 367 and 368 are all suitably mounted for slidable movement in a pin bar carrying frame 375 (see Fig. 31). This frame serves as a support for the spring 370.

Disposed below the pin bar assembly are a group of feeler bars 376 slidably mounted in a frame 377 and urged to the right by suitable springs 378. Individual bails 379 cooperate with shoulders on the feeler bars 376 to restore the same toward the left. These bails 379 are carried by a strip 380, Fig. 43, which is moved back and forth by means of a toggle device 381 having follower 382 cooperating with cams 383 one on each side of the machine, on shaft 265 (see also Fig. 26). With feeler bars 376 restored to the left their right hand ends will be substantially flush with one of the plates 377 (see Fig. 50). The distance which the particular feeler bar advances through this plate after the restoring bails 379 are moved away will determine the extent of elevation of type bars 385, said type carriers being elevated by suitable tension springs 386. For this purpose each type bar is provided with a stepped shoulder 387 having three upper steps and a lower notch 388 which with the parts in the lower position is in alignment with the lowermost feeler bar 376. This lower notch is utilized to prevent the raising of the type bar or bars, if there is no perforation in a particular column on the master card. Under these conditions a lug 389 on the lowermost feeler bar 376 is adapted to advance into a notch 390^a in the combs 373. If any of these combs 373 have been lowered, notch 390^a will move out of alignment with lug 389 and prevent the advance of the lowermost

feeler bar into engagement with notch 388 on its type carrier.

As previously explained, depending upon the combination hole arrangement, locations 5 in the card, various combinations of combs 373 will be allowed to drop varying extents. For convenience in reference these combs will be known as A, B and C. As shown in Fig. 50, the B comb cooperates with the mid- 10 dle pin bar group; the C comb with the lower pin bar group; and the A comb with the upper pin bar group. The combs 373 are provided with various combinations of comb slots so as to permit the pin bars 376 to differentially advance in accordance with the 15 factored combination of positions assumed by the vertical comb plates A, B and C. The operation of the combs will be fully described for normal position and for printing or for 20 controlling the operation of the bars for printing or perforating the letters V, N and 6. All of these characters are controlled by the feeler bar which is seventh from the top of the group (Fig. 50.) Fig. 53 shows a condition 25 of parts in which none of the combs A, B and C have lowered. This is the normal condition of parts. Under these conditions the lug 389 on the feeler bar will abut the unnotched edge of the B comb and consequently 30 the feeler bar will not advance into the path of the type carrier stepped stop 387. Fig. 54 shows a condition in which the B comb has lowered one step and the C and A combs two steps. This is indicated 35 by the arrows and is in accordance with the combinational hole system in the card for the letter V. With this condition of comb parts a notch 390 will align with lug 389 and notch 391 having a depth of one unit will 40 also align with the lug 389 and the third deep notch 392 will similarly align with the lug. Under these conditions the feeler bar will be permitted to advance one step and this will allow the stepped shoulder 387 45 on the type bars 385 to contact on the first step as shown, thereby positioning a type slug 393 representing V at the printing line. Under the conditions shown in Fig. 55 the B and C combs will have dropped one step 50 and the A comb will have dropped two steps. Under these conditions notch 390 will align with lug 389. On comb B a two step notch 391^a will have aligned with lug 389 and on the A comb the deep notch 392 will have 55 still remained in alignment with 389. Under these conditions feeler bar 376 may move two spaces to the right, stopping the stepped abutment 387 on the second step and aligning the type slug representing the letter N at 60 the printing line. Fig. 56 indicates the condition of parts for printing the numeral 6. Here comb B has descended one step; comb C no steps; and comb A two steps. Under this condition of parts, the deep notches 390 65 and 392 will align with lug 389 and the C

comb will have assumed a higher position to bring a three depth notch 391^b into alignment with the lug 389. With this condition of parts the feeler bar 376 will arrest the stepped abutment 387 on the top step thereby bringing the No. 6 type to the printing position. It will be understood that the pin combs 373 are notched their entire length to cooperate with the fifteen feeler bars. Each feeler bar carries a proper lug 75 389 for cooperation with the notches on the three combs and the combination of positions of these notches and their depth determine the differential forward advance of the feeler bars and thereby determine the 80 extent of elevation of the type carrying bars 385. It will be seen that the elevation of these bars 385 is differentially controlled in accordance with two factors. The first factor is the position of the particular feeler 85 bar selected, with respect to the remaining feeler bars. The second factor is the extent of advance of the particular feeler bar selected.

It will be borne in mind that Figs. 53 to 90 56 are diagrammatic and do not correctly illustrate the specific construction and relation of the parts. For example there is but one lug 389 on each feeler bar, but this lug extends over the face of the three combs, as 95 correctly shown in Figs. 57^a and 57^b.

To restore the combs 373 upwardly after the feeler bars have cooperated with the slots to take off a reading, a restoring bail 396 is provided. This restoring bail is actuated by links 397 from crank arms 398 on shaft 399, Fig. 43. Shaft 399 is in turn actuated by a linkage 400 (Figs. 44 and 62) which extends down outside of the frame 100 of the machine into cooperation with a cam 401 on shaft 265 (Fig. 26). After the type bars have moved to position under the control of the feeler bars, and after the feeler bars are withdrawn it is necessary to prevent the type bars from moving to extreme 105 upper position under the influence of springs 386. For this purpose the edges of the type carrier are provided with suitable notches shown in Fig. 57 and individual latches 110 395 cooperate with these notches. At the upper time in the cycle a latch control bail 402 fixed on shaft 403, Fig. 58, is actuated to permit the latches to engage the type bars under the influence of their springs. 115 Type bars 385 are restored in downward direction after the printing operation by restoring bail 405, Figs. 57 and 21^a, which bail is actuated by a link 406 connected to a rocker arm 407 having a depending link 407^a connected to a pivoted arm 408 having a follower cooperating with an internal cam 409. Prior to the restoration of the type bars latches 395 must be released. This 120 is effected by rocking shaft 403 which carries an arm 410 (Fig. 58) carrying a pin 125 130

cooperating with latch 404 (Figs. 21* and 70). Upon the downward movement of the type bar bail, actuated arm 407 and pin 411 carried thereby, will rock arm 410 clockwise thereby releasing the type bar latches 395 from the type bars. Thereafter latch 404 will engage the pin on arm 410 and prevent the relatching of latches 395 until a second pin 412 carried by the link 406 has engaged latch 404 upon the upward movement of the type bar restoring arm. This engagement will release latch 404 from arm 410 and permit the bail to reengage under the influence of the springs on latches 395.

15 The foregoing description has described the operation of a single type bar. There are a group of 25 type bars which correspond to the 25 column spaces on the master card. To the right of this group of 25 bars 20 there is shown a group of 10 type bars 413 which are utilized for printing and perforating numerical items upon the stub portion of the notice card. Referring now to Figs. 9 and 10 it will be noticed that there 25 is certain numerical data taken from field 101 which is not printed upon the first line of the body portion of the notice card and furthermore under ordinary operations it is desired to suppress the printing of a lapse 30 notice designation in field 118 on the stub. For this purpose during the first reading cycle when field 102 is read by the feeling pins, the action of certain type bars must be suppressed, otherwise all of the data 35 shown on field 101 of the master card will be printed on the notice card. For this purpose a bail 414 (Fig. 58) is provided pivoted on shaft 403 and having engaging shoulders 415 to suppress the operation of 40 certain type carriers. There is further provided on this bail a lug 416 which is adapted to engage the proper type bar of this group to cause the suppressing of the operation 45 of this type bar under ordinary conditions to permit 1 to be printed in lapsed condition when 416 is released from engagement with the type bar. It will be understood that the type bars 385 and 413 are properly notched at their lower ends to receive the locking bail shoulders 415 and 416. The bail 414 is operated at the proper time 50 in the cycle by a cam 417 mounted on cam shaft 262 (see Fig. 26). It will be understood that after the first line of the notice card is printed the bail 414 is locked to prevent the suppressing of the printing of 55 the succeeding lines.

As previously explained there are certain numerical data items taken from the first 60 line of the master card which data is printed in part at the first printing operation on the stub and which is suppressed in the second printing operation and then in part printed on the third printing operation and suppressed at the fourth printing operation.

It is therefore necessary to lock up the bars 413 which control the printing and perforating of the stub portion of the notice card during the second and fourth printing and perforating cycle. This locking up is 70 effected by means of a bail 417* which is similar to the bail 414 previously described and which cooperates with suitable notches in the bar 413. This bail is actuated at the proper time in the cycle of the machine by a cam 75 418 disposed upon shaft 262 (Fig. 26).

After the proper type slugs on type bars 385 are brought to the printing point they are impelled against an inking ribbon 420 (Fig. 57) disposed in front of the notice 80 card 116 by means of hammers 421. The ribbon feeding and reversing device are not herein illustrated or described in detail, as they are of conventional form. To drive the type slugs forward, striking pins 422 are 85 provided suitably guided on the printing line and adapted to be struck by hammers 421 pivoted on shaft 423. Fig. 50 shows the position of the hammer 421 prior to printing. Here they are shown latched by 90 latches 424. When the type bar 385 moves upwardly link 426 ascends swinging latch 428 into engagement with the hammer lock 424. After the proper type slug has reached the printing line shaft 427 is rocked thereby 95 rocking 428 to the right rocking hammer lock 424 counterclockwise and allowing the hammers to swing forward under the power of their springs and strike the striker pins. The cocking of the hammers is effected by a bail 425 which is pivoted upon a shaft 423. Shaft 423 is rocked for restoring the hammers by a linkage 430 shown in Fig. 21* 100 which extends to a bell crank 431 having a follower roller cooperating with a cam slot 432 in the type bar restoring bail arm 407. The hammer release shaft 427 is actuated at the proper time in the cycle by a suitable linkage 427* which extends to a striker pin 427* on a right hand cam 383 on shaft 265 105 (Fig. 70).

Referring again to the master card (Fig. 2) it will be seen that the only numerical items which are transferred to the stub portion of the check appear on the right hand 110 columns in the card. It is therefore not necessary to transfer all of the readings taken from the master card to the type carriers for the stub portion of the check. To effect 115 printing and perforating of the numbers on the stub portion of the data card or notice, transfer shafts 435 (Fig. 25) are provided. These shafts have individual depending 120 forked fingers 436 as shown in Fig. 31 which connect with the pins 128 through suitable pin collars. These transfer shafts extend to the right from the pins 128 and at their opposite ends are provided with similar 125 forked fingers 438 which connect with the dummy or non-card-reading pins 437 (see 130

Fig. 59). These dummy pins in many respects are similar to the reading pins heretofore described. They operate exactly in unison with the reading pins 128 to which they are connected. Similar comb selectors indicated generally 439 (Figs. 59 and 46), are provided to select combinations of positions of the two combs 440 and 441. It is here only necessary to use two of these vertical combs inasmuch as numerals and figures only are to be set up under the control of the combs. Cooperating with vertical combs 440 and 441 are four feeler bars 442 which carry the usual lugs cooperating with the notches of combs 440 and 441 and which are adapted to be projected in the path of the stepped stops 443 carried by the carrier bars 413. Restoration of the combs to normal position is effected by the same bail 396 which restores the main combs. The feeler bars are similarly retracted by bars 379. The carrier bars 413 move upwardly under the influence of springs 444 and restoration of these bars is effected by means of bail 405. The setting and restoring cycle for carriers 413 is substantially the same as heretofore described for the main carriers 385.

Inasmuch as only four feeler bars 442 are provided multiple stops 443, three in number, are provided on the carrier bars 413. These multiple stops are so arranged and the feeler bars so located that the type slugs 446 from zero to nine will be brought to the printing line upon the upward movement of the carriers.

The striking of the type against the paper is secured by means of hammers 450 provided with hammer locks 451. Restoration of the hammers 450 is secured by bail 452. This bail is fast upon shaft 423, the operation of which has been previously explained. Shaft 427 upon being rocked controls the tripping of the hammers.

Referring again to the notice card, Fig. 9, it will be noted that perforations are punched therein in fields 119 and 122 corresponding to the printed data in fields 118 and 121. To effect this perforation of the notice card a group of four punches 455 are provided (Fig. 60) mounted in suitable guides and cooperating with a suitable guide block 456 disposed at the rear of the stub portion 117 of the notice card. The carrier bars 413 are provided with spring retracted punch plungers 457 and the location of these plungers is such that they will align with the punches upon the displacement of the type carrier to bring a particular type at the printing line so as to effect the perforation of the stub portion of the card according to the quoted arrangement of holes heretofore described. Referring to Fig. 60, the No. 2 type slug 446 is shown at the printing line. The upper plunger 457 is in alignment with the second punch 455 from the bottom. This

will perforate a single perforation in the stub disposed in the second hole space from the bottom or the third from the top. This is in accordance with the hole combination of perforations as shown in Fig. 8. Fig. 61 shows a different set up for perforating holes corresponding with the numeral 3 which type slug is at the printed position. Here the two upper plungers 457 are in alignment with the second and fourth punches from the top as indicated by the arrows and upon the actuation of the plungers, perforations indicated at the second and fourth hole spaces will be made in the stub portion of the card. This corresponds with the code as shown in Fig. 8.

To effect the punching after the plungers 457 have selected a proper combination of punches the striking bail 458, as shown in Fig. 59, is normally out of the path of the punches. By movement of the bail 458 to the right, as shown in Fig. 60, the selected punch will be advanced through the card. Restoration of the punches is effected by means of restoring bail 459. Punch actuating bail 458 is actuated through a rocker cam follower 460 cooperating with a cam 461 on shaft 265, Fig. 21^a. This rocker arm 460 connects with a link 462 to rock a shaft 463. Shaft 463 is shown in reverse position in Fig. 62 and carries a crank lever 464, which, through a pin and slot connection, rocks a lever 465 connected to an upwardly extending link 466 which through a toggle linkage 467 is adapted to force the bail 458 connected thereto forward to actuate the punches. Both the actuating bail 458 and restoring bail 459 are carried by a sliding frame to which the toggle device 467 is connected. Restoration of the punches by bail 459 is secured by moving this frame to the right as shown in Fig. 62. This movement is secured by rocking bell crank 469, loosely mounted on shaft 463, clockwise by means of a roller 470 carried by a slide 471 connected to the main type bar restoring bail 405. A supplementary link 472 is provided to swing 469 in the path of roller 470 after the roller has moved upwardly and prior to its downward movement.

By the above operation the numerical data shown in field 118 is printed and the perforated data in field 119 is perforated on the stub portion of the notice card. It has been previously mentioned that the month designations on the stub are not taken from the master card but from a set up device in the machine. Referring now to Fig. 25 it will be seen that two feeler pins 437^a are provided which have no corresponding transfer shafts 435. These pins determine and control combs for determining the type bar and punch positions in perforating the month numerals on the stub portion of the check. Pins 437^a are controlled by a dial 342 which

- is provided with a series of rows of double perforations so arranged thereon as to bring the proper apertures into alignment with the corresponding pins 347^a in accordance with the month in which the dial 342 has been set by the month setting index when the pin group 347^a advances. The selected combination of pins will advance according to the month in which the machine is operating.
- As heretofore explained the printing of field 121 and the perforating of corresponding field 122 on the stub cannot be effected at the time of printing and perforating field 118 and 119. However, the numerical data in fields 121 and 122 are taken from the first printing operation on field 102 on the master card. Therefore it is necessary that certain of the numerical data taken from field 102 be stored somewhere in the machine so that printing and perforating can be effected in a later cycle. For this purpose cross combs are provided to take off a reading of the combs 373, which are displaced for numerical data and to store up the reading or relative downward displacement of the vertical combs 373 and afterwards to transfer the reading thus stored to the combs 440 which determine the movement of the type carrier and punches for the notice section of the machine. It is not necessary to provide cross combs for all the columns on the master card. No transfer is needed for alphabetical items and only certain numerical columns are to be transferred. As shown in Fig. 50 the vertical combs 373 for numerical items have depending lugs 480. It is these lugs which cooperate with the cross combs which are generally indicated at 481 in Fig. 50.
- Twenty cross combs are provided. Each cross comb cooperates with a particular vertical comb. Inasmuch as these vertical combs are required for determining a particular 10 columns of figures can be transferred by the cross combs.
- Referring now to Fig. 63 the cross combs 481 are shown in their normal home position. The first operation is for the vertical combs 373 to descend in accordance with the card reading as heretofore explained. The tails 480 then descend differentially 1, 2 or 3 steps as heretofore explained. These tails 480 thus move in the path of stepped abutments 482 carried by the cross combs. After such descent of the vertical combs 373, the cross combs are bodily displaced to the right until arrested by the contact of the tail 480 with a particular step of abutment 482 (see Fig. 64). As shown in Fig. 44 the cross combs 481 are slidably mounted in a cross comb carriage 483 having a three step spring aligning detent 484. Cross combs 481 are in themselves slidably mounted in the cross comb carriage 483 and are normally drawn to the right thereof by
- springs 485 (see Fig. 63). To set up the cross combs in the position shown in Fig. 64 the cross comb carriage 483 is first moved to the right by means of a shoulder arm 486 shown in Fig. 44 which shoulder arm is operated by complementary cams 487 on a cam shaft 148 (see Fig. 21). Arm 486 moves the cross comb carriage first to the second notch engaged by detent 484. By such movement the cross combs will follow the carriage 483 in its movement to the right and will be arrested by a tail 480 engaging one of the steps 482. If the cross comb carriage 483 moves further than permitted by tail 480 and stepped abutment 482, springs 485 will yield and permit the cross combs 481 to remain stationary during the continued right hand movement of the carriage. Immediately after the cross comb carriage 483 has commenced to move to the right the spring pressed pawl 488 will be freed from engagement with a stud 489 and will swing into engagement with the ratchet teeth 490 on the face of the cross combs (see Fig. 64). The steps of ratchet 490 correspond with the horizontal width of steps 482 and hold the cross comb in the position which they assume under the control of the tails 480. The above describes the method of taking a cross comb reading from the vertical combs 373. Thereafter the vertical combs 373 are withdrawn upwardly preparatory to being set for controlling the printing of a second line on the body portion of the notice. Thereafter the cross combs are displaced further to the right to bring the third alignment notch into engagement with the spring detent 484 (see Fig. 64^a). This movement is effected by the cams as before. Upon the right hand ends of the cross combs 481 are stepped abutments 482^a identical with 482 and underlying tail 480^a depending from the vertical combs 440 which control the numerical perforations on the stub of the notice. After the cross comb carriage has assumed this position in the third notch the vertical combs 440 are permitted to descend to bring their tails 480^a into contact with the steps of 482^a. This set up of parts takes place at the time that field 106 is being read from the master card and during the printing of field 105. Thereafter the printing operation of field 121 and the perforating operation on field 122 is effected on the stub in the manner heretofore explained. After the vertical combs 440 are restored the cross comb carriage is again returned to the right by means of the cams 487 and eventually the pawl 488 will contact with the stop 489 permitting the springs 485 to return any displaced cross combs to their right hand positions preparatory to a new operation. For clearness diagrammatic Fig. 65 shows the initial position of a single cross comb

with respect to tails 480 and 480^a. Fig. 66 shows the second condition in which the tail 480 has arrested cross comb 481 by contact with step 482. Fig. 67 shows a transferred position in which the cross combs have moved to the right to bring stepped abutment 482^a under tail 480^a, and arrest its vertical comb in correspondence to the other vertical comb, having tail 480 connected thereto.

During cross comb operations, it is essential that the operations of the dummy pins under the control of the transfer shafts be suppressed, otherwise confused readings would result due to the fact that other data is being read from the card by the feeding pins 128 and such data would be transferred by the transfer shafts to the notice section of the machine where it would commingle with the numerical data stored from the cross combs. For this purpose the pin bars which are connected to pins 437 and 437^a are provided with lugs 495. Cooperating with these lugs are bail fingers 496 carried by a shaft 497 (see also Fig. 46). By rocking these bail fingers 496 to the left as shown in Fig. 59 the pin bars will all be withdrawn to the left to permit the free descent of vertical combs 440 and 441 and their arrest by the cross combs 481 as previously explained. During this operation springs 363 on dummy pins 437 yield and allow the pins 437 to remain stationary so as not to displace pins 128 to which they are connected by transfer shafts 435. Shaft 497 is rocked at the proper time in the cycle by a linkage 498 shown in Fig. 21^a which extends to and connects to a pivoted arm 499 having a follower cooperating with a cam 500 mounted upon cam shaft 262.

The machine in the printing section comprises the usual split device for suppressing the printing of zeros at the left of the last significant figure. Such split devices being old and well known in the accounting machine art, are not herein illustrated, described or claimed.

For convenience in illustration and description certain parts of the machine have been shown in displaced position. In order that the exact cycle operation of these parts will be clear and the successive movements of the different sections of the machine will be understood, a timing chart is shown in Fig. 71.

This timing chart may be briefly explained as follows: It will be assumed that the position marked beginning of the machine cycle and master card is at the A position. After a slight clearance interval the pins go in. Pins 124, 125, 126, 127 and 128 go in and take a reading from the master card. Following a slight clearance the vertical combs 373 and the vertical combs 440 and 441 take a reading from the pins. During

this part of the cycle drop levers 279, 279^a and 278 drop. The next part of the cycle is the taking of the reading by the feeler bars 376 and 442. During this portion of the cycle the pins are withdrawn from the card. Next the type bars go up. Following this the printing and punching operation is effected. The punches are then withdrawn, hammers rocked, etc., stop pieces or feeler bars 376 are withdrawn from the comb. Following this operation the combs 373 are arrested. This is the end of the first reading cycle on the master card. This cycle is substantially repeated for the succeeding three reading cycles. Certain subsidiary operations which take place during the first cycle are shown in the next outer circle. The following circle steps show the operation which takes place at the first cycle; the next circle shows the operation which takes place at the second cycle; and the next circle shows the operation which takes place at the third cycle.

Hereafter in the claims I shall refer to the term "controlling record" as designating the master card or sheet from which the machine takes its reading of controlling perforations. The term "second record or sheet" refers to the receiving record which receives the transferred records from the master card. Although the machine is particularly adapted to use individual cards, it is not intended that the scope of the invention be specifically limited to cards. Any suitable perforated sheet may be used for the master or controlling record. Likewise the notice may be a card or sheet, and need not necessarily be entirely blank. The term "blank" is intended to set forth that the receiving sheet has suitable blank space to receive a further printed or perforated record. Printing and perforations may be already upon this sheet if desired. The term "recording" means the making of a record in any way, either by printing or perforating. Similarly the word designation broadly includes either a printed or perforated marking of a sheet.

The invention also is not limited to the particular use herein fully explained, i. e., that of making insurance notices from master cards. In its broad aspects the machine is adapted for the transferring of any form of record from controlling perforations to a receiving sheet or record of any form and for any desired purpose.

Certain features of the present invention relating to the reading of the combination hole system by the machine and setting of record making means in accordance therewith are claimed in a separate copending application Serial No. 566,449, filed June 7, 1922.

What I claim is:

1. A perforated record card having a

plurality of perforation receiving fields therein, each field having six hole spaces therein, combinations of from one to a maximum of three perforations variously disposed in said six spaces to individually represent by their number and disposition the letters of the alphabet or other characters, at least five of said different combinations being each represented by a single perforation.

2. A perforated card having a plurality of perforation receiving fields therein, each field having six hole spaces therein, combinations of one to a maximum of three perforations variously disposed in said six spaces to individually represent by their number and disposition alternatively either the letters of the alphabet or the individual digital characters, each field of six hole spaces being adapted to receive combinations of holes to represent either letters or digits.

3. A perforated record having a plurality of perforation receiving fields, each field having a plurality of hole spaces, perforations in said spaces of less number than the number of hole spaces in each field for representing individual characters, said perforations and hole spaces in number for each character being the theoretical minimum possible for representing the entire alphabet and digits.

4. A perforated record card having alphabetical and digital characters thereon represented by combinations of holes, said card having hole spaces allocated to receive said holes, the total number of hole spaces being the minimum possible number for representing the total number of characters.

40 5. The invention set forth in claim 4 in which the minimum possible number of holes are provided in said hole spaces to represent the total number of characters.

45 6. A perforated record card having a plurality of hole spaces thereon, combination of perforations in said hole spaces having a total number of holes less than the number of such spaces for representing individual alphabetical characters, and other combinations of perforations variously arranged in said spaces of less maximum total number than the maximum total number for the individual alphabetical characters for representing individual numerical numbers.

55 7. A perforated record card having a plurality of perforation receiving columns each having six hole spaces therein, combinations of from one to three perforations variously disposed in said six hole spaces to individually represent the letters of the alphabet,

60 65 8. A machine for compiling records from combinations of from one to two perforations otherwise variously disposed in said six hole spaces to individually represent numerals.

a perforated card having perforations therein representing both alphabetical and digital characters, said machine comprising mechanism for reading the perforations on the card and utilizing the theoretical minimum number of hole spaces which can be used for the alphabetical and numerical characters and for also utilizing the theoretical minimum number of perforations in said hole spaces.

9. A perforated record card adapted to be utilized in a machine for recording data, said record card having two types of zones or fields therein upon which perforated records may be placed, one zone having perforated card data adapted to give a reading to the machine and to be transferred upon a receiving record, and a second set of zones which by their perforations determine whether any or no reading shall be made upon the blank record.

10. In a card controlled apparatus, the combination, with a record card having a plurality of annual fields, perforations in the card which allocate the different fields to specific years, and means for reading said perforations and thereby determining the operation of the apparatus.

11. In a card controlled apparatus, the combination, with a record card having a plurality of annual perforated fields, means for reading said fields, means for setting up the machine for a particular year, and means for permitting the effective operation of the machine provided one of the perforated fields agrees with the annual set up of the machine.

12. In a card controlled machine, the combination of a record card having perforations denoting years, set up devices in the machine denoting a single year in which the machine is operating and means controlled from the card for permitting the effective operation of the machine provided the annual set up of the machine agrees with any one of the annual fields on the card.

13. A machine for transferring items from a controlling perforated record to a second record, said machine having provisions for making a designation upon the controlling record when perforated data therefrom is transferred to a second record.

14. A machine for transferring items from a controlling perforated record to a second record, said machine having provisions for making a special designation upon said second record when the controlling perforated record indicates an unpaid condition.

15. A machine for transferring items from a controlling perforated record to a second record, said machine having means determined by the perforations of the controlling records for permitting or suppressing the making of said second record, and

means effective upon the making of said second record for perforating the controlling record to designate that a second record has been made.

5 16. A machine for transferring items from a controlling perforated record to a second record, said machine having provisions for suppressing the making of a designation upon the controlling record when perforated data therefrom is not transferred to the second record.

10 17. In a machine for transferring items from a controlling perforated record to a second record, said machine having provisions for making a designation upon the controlling record, and means for suppressing the transferring of data to the second record under certain conditions of the perforations of the controlling record.

20 18. A machine for transferring items from a controlling perforated record to a second record, said machine having provisions for transferring data from the controlling record to the second record only upon the agreement between certain items on the controlling record with a set up device in the machine coacting with such controlling items.

30 19. A machine for transferring items from a controlling perforated record to a second record, said machine having provisions for making a designation upon the controlling record indicative of the controlling record having passed through the machine under certain conditions of the perforations of the controlling record.

40 20. A machine for transferring items from a controlling perforated record to a second record, said machine having provisions for selecting a field upon the controlling record and means in said machine for making a designation in said selected field to show that a second record has been made from the controlling record.

45 21. A notice making machine controlled by perforated record card, said machine having provisions for making notices with data thereon corresponding with perforations of passing record cards, means for setting the machine, means for suppressing the making of a notice if said set up in the machine fails to correspond with certain perforations of the passing record cards.

50 22. A notice making machine having provisions for making notices with data thereon corresponding to the perforations of passing cards, means for suppressing the making of a notice when the payment perforations on the passing cards indicate a prepaid status.

60 23. In a card control apparatus, in combination, a record card perforated with a plurality of independent groups of perforations denoting years, means for reading the said record card perforations and means

for suppressing the effective operation of the machine if none of the groups of perforations on the card coincide with the year in which the machine is operating.

70 24. A machine for transferring a record from a controlling perforated record to a second record, said controlling record having several zones allotted to certain periods of time and means for determining which zone is active when the controlling record is being actively operated upon by the machine.

75 25. A machine for transferring a record from a controlling perforated card to a second record, said machine requiring more than one revolution to complete the operation of transferring data from the controlling card to the second record.

80 26. A machine for transferring records from controlling perforated records to secondary records, said machine requiring more than one revolution to complete its transferring cycle.

85 27. A multiple revolution perforated card control machine, said machine having provisions for reading data from perforations of the card, means in said machine operable during different revolutions of a single cycle for suppressing operations during certain revolutions and means for calling into action other portions of the machine during other revolutions.

90 28. A perforated record controlled machine requiring more than one revolution of the same to complete its cycle of operations, means in said machine for simultaneously reading a plurality of perforations in the controlling record, and means for controlling the operation of the machine to permit repeated operations upon a single controlling perforated record.

95 29. In a card controlled machine, in combination, means for feeding controlling perforated records and receiving sheets through the machine, means for reading the controlling perforations on the controlling records and transferring the data thus read to the sheets and supplementary means in said machine for controlling the transferring of data in accordance with the absence or presence of certain perforations in the controlling records.

100 30. In a card control machine, in combination, with feeding devices for feeding controlling perforated records and record receiving sheets through the machine, means for reading the controlling perforations, means for transferring the reading thus obtained in more than one form to the receiving sheets.

105 110 115 120 125 130 31. In a card control machine, in combination, with feeding devices for feeding controlling perforated records and blank sheets therethrough, means for reading the perforated records, means for transferring

- the readings thus obtained to the blank sheets and means for placing said transferred records upon the blank sheets in two ways, first, by printing upon the sheets and second, by perforating the same.
32. In a card control machine, in combination, with feeding devices for feeding controlling perforated records and blank sheets therethrough, means for reading the controlling perforations and for transferring the readings thus obtained to the blank sheets and means for placing said transferred records upon the blank sheets in two ways, first, by printed record and second, by a printing and perforated record.
33. In a card control machine, in combination, with feeding devices for feeding perforated controlling records and blank cards having two separable portions therethrough, means for reading the perforations of the controlling records, means for transferring the readings to the cards, said last mentioned means having provisions for placing the records on both portions of the cards.
34. The invention set forth in claim 33 in which a record of certain items are repeated on both portions of the card.
35. A duplicating machine controlled by perforated records, said machine having means for duplicating the record as perforated, and means in said machine for duplicating certain items on the said duplicated record.
36. A transferring machine for transferring items from a controlling perforated record to a second record, said controlling record having a plurality of perforated fields thereon, each of which has a plurality of controlling perforations therein, means in said transferring machine for successively taking the readings from the different perforated fields on the controlling record and means for transferring said readings to the second record.
37. A transfer machine for transferring items from a controlling perforated record to a second record, said controlling record having a plurality of perforated fields thereon, means in the transferring machine for simultaneously taking readings from a plurality of perforations in one field and for successively taking other simultaneous readings from the other fields of the controlling record, means for transferring the readings thus taken to the second record by printed and perforated designations.
38. A transferring machine for transferring records from controlling perforations of one record to a second record, said controlling record having a plurality of perforated fields therein, each field having a plurality of controlling perforations, means in the transferring machine for successively presenting the various fields of the control- ling records to reading devices and means for transferring the readings thus taken to the second record.
39. The invention set forth in claim 38 in which means is provided for successively moving the second record to present different portions thereof to the record making devices whereby data will be marked upon the second record in a plurality of fields.
40. In a machine for transferring records from a controlling perforated record to a second record, in combination, with the controlling record reading devices, transferring devices and second record making devices of means for controlling the operation of the aforesaid devices, said means comprising elements controlled conjointly by the co-action of mechanism in the machine and by perforated data on the controlling card.
41. In a card control machine, means for feeding perforated controlling record and receiving record cards through the machine, means for taking readings of the data upon the controlling record cards, means for transferring certain data thus read directly to the receiving cards, means for temporarily storing other data in the machine and thereafter transferring same to the receiving card at a time subsequent to the receipt of the first mentioned data thereby.
42. In a card control apparatus, in combination, means for taking readings from the controlling perforations and record cards, combs controlled in their combination of positions by said perforations, record making devices controlled by the combination of positions taken by said combs, a supplementary set of record making devices for making other portions of the same record, a set of combs for controlling said last mentioned record making means and means for transferring the setting of the first mentioned set of combs to the second mentioned set of combs for the purpose described.
43. The invention set forth in claim 42 in which cross combs are provided for transferring the settings from the first mentioned combs to the second mentioned combs.
44. A card controlled apparatus, in combination, perforation reading means, a plurality of combs controlled thereby and record making devices controlled by said combs, a second set of record making devices, a plurality of combs for controlling the same and multiple means for controlling the positions of said second mentioned combs.
45. The invention set forth in claim 44 in which one of said multiple means comprises transfer means coacting directly with the perforation reading means and in which the second mentioned means comprises devices coacting with the first mentioned set of combs and adapted to transfer the set-

tings thereof to the second mentioned combs.

46. In a machine for transferring items from a controlling perforated record to a second record, in combination, with a controlling record card having perforations therein indicative of the months in which the second records are to be made out, means in the machine for sensing said perforations, and means controlled thereby for suppressing the making of a second record if said monthly perforation does not correspond with the month in which the machine is operating.

47. In a machine for transferring items from a controlling perforated record to a second record, in combination, with a controlling record having perforations therein designating the months in which said second records are to be made out, means in said machine for reading said monthly perforations, and means in said machine for permitting the making of a second record if a monthly perforation agrees with the month in which the machine is operating.

48. In a machine for transferring items from a controlling perforated record to a second record, in combination, with a record card provided with a perforation indicating that a second record is to be made out each month, means in the transferring machine for reading said perforation, and means controlled by the aforesaid means for permitting the making of a second record upon the taking of said reading.

49. A machine for transferring a record from a controlling perforated record to a second record, in combination, with a controlling record card provided with various fields to receive controlling perforations, means in said machine for reading said controlling perforations and determining by their character the making or suppressing of a second record, means in the machine for making a designation upon the controlling record indicative of the making of a second record, and means controlled by the perforations of the controlling record for determining the zone or field in which said designation is to be made.

50. In a card controlled machine of the class described, the combination, with a plurality of feeling pins, means for advancing same into contact with a card and for advancing certain pins therethrough, a plurality of pin bars displaceable upon the advancing of one or more of said feeler pins, vertical combs controlled in their movement by the combinations of advanced pin bars, a plurality of feeler bars controlled by the conjoint displacement of said combs, record making devices controlled by the said feeler bars, means for displacing the pins, means for moving the vertical combs, means for advancing the feeler bars and means for

moving the record marking devices into cooperation with the feeler bars.

51. In a card controlled machine of the class described, in combination, with a picker adapted to advance cards one by one from a storage stack, a reciprocating carriage adapted to receive cards from said picker and move the same through the machine to a discharge stack, and means for interrupting the operation of the machine should a card be disengaged from the card engaging means on the said carriage.

52. In a card controlled machine, in combination, with a plurality of reading devices for reading the perforations of a controlling record card, each group of reading devices being adapted simultaneously to read a plurality of controlling perforations, card feeding means adapted to advance cards into cooperation with said reading devices, and a supplementary card feeding device adapted to move said cards to present successive fields thereof to said reading devices.

53. In a card controlled machine, in combination, with card feeding devices for advancing cards from a storage stack to a reading station and thence to a discharge stack, in combination, with a supplementary card carriage adapted to receive the cards when they are at the reading station and to advance the same in a different path to present successive portions of the cards to the reading devices.

54. In a machine of the class described, in combination, with card feeding devices having clips to engage controlling record cards and advance the same through the machine, a second set of card feeding devices with means for grasping blank cards and advancing the same through the machine, means for transferring records from one controlling perforating card to a blank card, and means for interrupting the operation of the machine should either a blank card or a controlling card become disengaged from its controlling or feeding device.

55. In a machine of the class described, in combination, with storage and discharge stacks for controlling record cards and blank record cards, means for feeding the controlling and blank cards from their discharge to storage stacks, and means operable during such transfer of the cards for reading the controlling cards and transferring the data to the blank cards.

56. The invention set forth in claim 55 in which means is provided for advancing both the controlling record and the blank record in a path different from the direct path from the storage to discharge stack whereby a plurality of successive readings of records may be taken from the controlling cards and placed upon the blank cards.

57. In a machine of the class described, a

- reading station adapted to read the perforations of controlling record cards, means for advancing controlling record cards horizontally to and away from said station, and 5 means for advancing the controlling means vertically with respect to said station to permit successive readings to be taken therefrom at different positions thereon.
58. In a card controlled machine of the 10 class described, in combination, with means for feeding record receiving cards to and away from a record making station and means for displacing said record cards vertically relatively to the recording station 15 to make a plurality of superimposed records thereon.
59. In a machine for transferring records from a controlling perforated record card to blank record cards, means for feeding 20 the controlling and blank record cards in a horizontal path to record reading and record making station, means operable when said cards are at said stations for effecting a relative displacement of the cards relatively to the reading and record making 25 means whereby superimposed fields upon the controlling record may be read and superimposed records may be made upon the blank cards.
- 30 60. In a machine for transferring data from a controlling perforating record to a second record, in combination, means for taking readings from various perforated fields of the controlling record, means for recording said readings in superimposed lines upon the second record and means for withholding in the machine certain records taken from certain fields of the controlling record and for recording the same upon the 40 second record during the reading of different data on the controlling record.
61. In a machine for transferring data from a controlling perforated record to a second record, means for independently 45 reading different fields of the controlling records, means for transferring and recording the readings upon the second record and means for suppressing the recording of certain items read from the controlling record.
- 50 62. The invention set forth in claim 61 in which means is provided for storing the readings which are suppressed and for thereafter recording said readings at a subsequent recording operation upon the second record.
- 55 63. In a card controlled apparatus in which blank cards are successively passed through the machine, means for recording items upon said blank cards and means operable upon the failure to feed of the blank card for suppressing the operation of the 60 machine.
64. In a card control apparatus, in combination, a reading station, means for advancing cards in a straight line to and away 65 from said reading station, and means for advancing said cards at said reading station in a path at right angles to the first to permit successive readings to be taken on the same card.
65. In a card controlled machine, in combination, means for feeding master cards successively from a storage stack through the machine, means for successively feeding other cards through the machine, means co-operating with the said master cards for 70 imprinting data upon the correlated other cards.
66. In a card controlled machine, in combination, means for taking perforated master cards successively from a stack and feeding the same through the machine, means for successively feeding other correlated cards therethrough and means to co-operate with the master card perforations of each successive master card for transferring 75 data to the proper correlated card.
67. In a card controlled machine, in combination with card feeding devices for perforated master cards and data receiving cards, means for presenting various data 80 fields of the master cards to common reading devices, said reading devices each having provisions for simultaneously reading a plurality of perforations on the master card 85 designating a line of characters, and means for transferring the data obtained from each field on the master card to a data card.
68. In a card controlled machine, in combination, means for feeding perforated record cards through said machine, means for feeding data receiving cards therethrough, means for successively taking a series of data readings from each perforated card, means for comparing certain of the said data derived from said cards with set up devices 105 in the machine, means for transferring other data to the data cards, and means for transferring to the record cards data indicative of the transference of data by the machine to the data card.
69. In a card controlled machine, in combination with card feeding devices, means for taking data from perforated cards; means for comparing certain data derived 110 therefrom with set up devices in said machine, means for transferring other data from said cards to correlated cards provided the first mentioned data agrees with the data set up on the set up devices in said machine.
70. In a card controlled machine, in combination, with perforated record and data card feeding devices, means for feeling the perforations of the record cards to thereby obtain data therefrom, means for imprinting the data thus received upon the data 115 cards, and means for perforating the correlated records upon the data cards.
71. In a machine for transferring addresses from a group of successively zoned sheets having perforated records thereon in 120

combination, means for feeding the perforated record sheets through the machine, means for sensing the perforated address data therefrom and means for transferring 5 said data by printing devices to receiving sheets.

72. In a card controlled machine, in combination, with a master card having perforations thereon optionally disposed in the 10 same record field or column and designating either numerical items or alphabetical characters, master and receiving card feeding means, reading devices adapted to take off readings, from said perforations, a receiving sheet or card and means for transferring 15 such readings to said sheet.

73. In a card controlled machine, in combination with a card having perforations therein optionally disposed in the same field 20 or column and representing either numerical items or alphabetical characters, card feeding means, reading devices adapted to take off data readings from said perforations, a receiving card and means for transferring 25 thereto the readings taken from the aforesaid first mentioned card.

74. In a card controlled machine, in combination, with master and data card feeding means, means for taking readings from the 30 perforations of the master cards, said means having provisions whereby a plurality of perforations in one field may be read simultaneously, means for successively presenting various fields of the master card to said reading means whereby data may be taken individually from each field, and means for transferring such data to the data card.

75. In a card controlled machine, in combination, with master and data card feeding 40 means, means for taking readings from the perforations of the master cards, and for transferring such data to the data cards and means for taking other readings from the perforations of the master card and controlling the action of the machine.

76. In a card controlled machine, in combination, with perforated master and data card feeding means, means for taking readings from the perforations of the master cards, means for transferring the data readings thus taken to the data cards, and means for indicating such transfer by a designation 50 upon the master card.

77. In a record-sheet-controlled machine, 55 means for analyzing data in a plurality of fields of a record sheet, separate means for making a record in each of such fields, and means controlled by said analyzing means for rendering one of said record-making 60 means operative.

78. In a machine adapted to be controlled by record sheets, means for analyzing data in a plurality of fields of a record sheet, separate means for making a record in each of such fields, means for selectively render-

ing said record-making means operative, said selective means being controlled by said analyzing means.

79. In a machine adapted to be controlled by record sheets, means for analyzing data 70 in a plurality of fields of a record sheet, said means being adapted to ascertain which of such fields contains predetermined data and means controlled by said first named means for making a record upon the sheet. 75

80. In a machine adapted to be controlled by record sheets, means for analyzing data in a plurality of fields of a record sheet, said means being adapted to ascertain which of such fields contains predetermined data, and 80 means controlled by said first named means for making a record in the field found to contain such predetermined data.

81. In a perforated-record-controlled apparatus, means for simultaneously feeding a 85 plurality of records through the machine, and means for comparing one of the records with a set-up in the machine for controlling the operation of the machine.

82. In a record-controlled machine, the 90 combination with a record sheet having a plurality of fields, of means for analyzing perforations in said fields, means controlled by said analyzing means for posting data in at least one of said fields, and set-up means for 95 determining the position within the field for the posting of such data.

83. In a record-controlled machine, record analyzing means adapted to analyze a plurality of fields of a record, means controlled 100 by said analyzing means for posting data in at least one of the fields, and a set-up device for determining the position within the field for the posting of such data.

84. In a record-controlled machine, record analyzing means adapted to analyze a plurality of fields of a record, a set-up device 105 cooperating with said analyzing means, said means and device acting conjointly as a field selector, and means for posting data in a 110 field selected by said analyzing means and device.

85. In a record-controlled machine, means for sensing data in a plurality of zones on a record, a set-up device, zone selecting means 115 controlled by said sensing means and said device, and data posting means controlled by said selecting means.

86. In a record-controlled machine, data-sensing means, combination combs positioned 120 under control of said sensing means, posting combs positioned under control of said combination combs, and record posting means controlled by said posting combs.

87. In a record-controlled machine, means 125 for analyzing identification data on a record, additional identification data analyzing means, and a record making device controlled by both of said means.

88. In a record-controlled machine, means 130

for recording and comparing data on a plurality of elements, at least one of which elements is a record sheet, and means controlled by said reading and comparing means for effecting an additional record.

89. In a data-comparing machine, means for sensing data on a plurality of records successively, additional data-controlled elements, means for comparing said sensed data 10 with said elements, and means brought into operation when data represented in said elements is not matched by the data being sensed for effecting a predetermined operation of the machine.

90. In a record-controlled machine, record analyzing means adapted to analyze a plurality of fields of a record, a set-up device cooperating with said analyzing means, said means and device acting conjointly as a field selector, means for posting data in a field 15 selected by said analyzing means and device and means for determining the position within the selected field for the posting of such data.

In testimony whereof I hereto affix my signature.

JOHN ROYDEN PEIRCE.
